UNITED STATES PATENT OFFICE

138,220

DESIGN FOR A BRIDGE SCORER

Robert H. Benson, Minneapolis, and Dean Root,
St. Paul, Minn.

Application September 20, 1943, Serial No. 111,168

Term of patent 3½ years

(Cl. D34—5)

To all whom it may concern:

Be it known that we, Robert H. Benson and Dean Root, citizens of the United States and residing in the city of Minneapolis, Hennepin County, State of Minnesota, and St. Paul, Ramsey County, and State of Minnesota, respectively, have invented a new, original, and ornamental Design for a Bridge Scorer, of which the following is a specification, reference being had to the

accompanying drawing, forming a part thereof.

The figure is a top perspective view of a bridge scorer, showing our new design.

We claim:

The ornamental design for a bridge scorer, as shown.

ROBERT H. BENSON,
DEAN ROOT,
